Application October 21, 1943, Serial No. 507,127

4 Claims. (Cl. 235—61.5)

1

This invention relates generally to electronic computers, and particularly to an improved method of and means for converting the values of the polar coordinates of a point in space to binary quantities corresponding to the values of the rectangular coordinates of said point.

The present application is a continuation-in-part of application Serial No. 466,397, filed November 21, 1942.

Frequently the firing data obtained from artillery sighting apparatus is in the form of the polar coordinates of the target. It is often desirable to compute the ballistics equations incidental to sighting a gun in the terms of the rectangular coordinates of the target. Therefore, a continuously operated device which will provide the conversion from polar to rectangular coordinates is highly advantageous.

The angular and distance polar coordinates of the target may be translated into electrical data in the form of a combination of potentials corresponding to binary numbers. A binary number of p binary places can be represented by p potentials, each having one of two values V_1 or V_2 depending as to whether the corresponding digit is zero or one. These p potentials can be carried on a system of p conductors. The codal effect of the energization of these conductors to the potential V_1 or V_2 represents the binary number. The polar coordinates of a point are represented by a horizontal angle, a vertical angle, and a distance from a reference point on a reference line. The rectangular coordinates x, y, z of the point may be obtained by deriving the sines and cosines of the two angles and combining them to fulfill the conditions of the following equations:

$$(1) z = D \sin \epsilon$$

$$(2) x = D \cos \epsilon \cos A$$

$$(3) y = D \cos \epsilon \sin A$$

Where the line D represents the distance of the point in space from a predetermined point O on a reference line, A is the horizontal angle between the X -axis and the horizontal projection of the line D , ϵ is the angle between the line D and its horizontal projection, and the Z axis is assumed to be vertical.

By means of well known trigonometrical equations, it will be seen that

$$(4) x_0 = \cos A \cos \epsilon = \frac{1}{2} [\cos (A+\epsilon) + \cos (A-\epsilon)]$$

$$(5) y_0 = \sin A \cos \epsilon = \frac{1}{2} [\sin (A+\epsilon) + \sin (A-\epsilon)]$$

$$(6) z_0 = \sin \epsilon$$

2

if the distance D is assumed to have unit value. The particular values of the rectangular coordinates at any instant will therefore equal Dx_0 , Dy_0 and Dz_0 , respectively.

The above mentioned sines and cosines of the angles ϵ and A may be obtained in terms of binary numbers by means of rotating discs provided with fiducial marks calibrated in terms of the sine of the angle of rotation.

- 10 If a first shaft is rotated through the vertical angle ϵ , and if the shaft is secured to a disc having light responsive fiducial marks in terms of the binary numbers corresponding to the sine of the angle of rotation, a fixed mask including a 15 slit disposed radially across the disc, will expose to voltage generating devices the fiducial marks representative of the sine of the angle ϵ .

The first disc may be arranged to drive two other normally disposed discs of similar type.

- 20 The last mentioned discs may be floated at their centers on a second shaft disposed normal to the first mentioned shaft. Slotted fixed masks, disposed at right angles to each other, may be secured to the second shaft adjacent each of the 25 last mentioned discs. When the second shaft is rotated through an angle corresponding to the horizontal angle A , the slits in the fixed masks disposed adjacent each of the last mentioned discs will expose to voltage generating devices

- 30 the fiducial marks corresponding to the sine and the cosine of the angle of rotation A . The last mentioned discs may be arranged to rotate in opposite directions in response to rotation of the first shaft through the vertical angle ϵ . It 35 will therefore be clear that rotation of the shafts through the angles ϵ and A , respectively, will unmask fiducial marks characteristic of the sine of the angle ϵ and the sine and cosine of the angles $(A+\epsilon)$ and $(A-\epsilon)$.

- 40 The fiducial marks may be translated into electrical data as they move past the narrow slit in each mask and are exposed to light sources and light sensitive devices arranged on opposite sides of the discs carrying the fiducial marks. The 45 various fiducial scales, which will be described in detail hereinafter, will therefore activate predetermined ones of the light sensitive devices, depending upon the angular position of the particular mask with respect to the particular disc.

- 50 The electrical data so derived will be in the form of fixed voltages for any one position of the mask with respect to a selected disc. These voltages may be applied to an electronic counter, for example, of the type described in the copending 55 application of George A. Morton and Leslie E.

Flory, Ser. No. 464,292, filed November 2, 1942, Patent No. 2,409,689, entitled "Electronic computing devices." This copending application describes a means of adding and multiplying numbers represented through the medium of voltages representative of the different digits of the numbers. Voltages thus corresponding to the cosines of the sum and difference of the horizontal and vertical angles are applied to one of these counters, while voltages corresponding to the sines of the sum and difference of the angles are applied to a second such counter. As explained heretofore, the voltages derived in accordance with the instant invention are in terms of the binary number corresponding to the value of the particular function.

A fourth disc may be secured to a shaft which is rotated through an angle proportional to the distance of the point in space from the reference point. The fiducial marks on the fourth disc may be arranged to actuate additional light sensitive devices, to provide voltages representative of the different digits of the number corresponding to this distance.

The voltages thus corresponding to the value of the sine of the angle ϵ in terms of a binary number, and the voltages corresponding to the distance of the point, may be applied simultaneously to a first multiplier circuit of the type described in the copending application of Leslie E. Flory, Ser'l No. 467,229, filed November 11, 1942, now abandoned, which describes an electronic multiplying device for two or more binary numbers. The product derived from this first multiplier circuit will be equal to the binary value of the z rectangular coordinate of the point in space. Likewise, the output of the first counter mentioned heretofore, and the voltages characteristic of the binary value of the distance, may be applied to a second electronic multiplier circuit from whence the product will be proportional to the binary value of the x coordinate of the point in space. Similarly, the output of the second counter and the voltages corresponding to the distance may be applied to a third electronic multiplier, from whence the binary equivalent of the y rectangular coordinate of the point may be derived.

Among the objects of the present invention is to provide an improved method of and means for converting the values of the polar coordinates of a point in space to corresponding values of the rectangular coordinates of said point. Another object is to provide an improved method of and means for deriving electronically voltages representative of the digits of the binary numbers corresponding to the rectangular coordinates of a point in space when the polar coordinates of said point are known. A still further object of the invention is to provide an improved method of and means for deriving voltages representative of the digits of the binary values of the rectangular coordinates of a point in space when the polar coordinates of said points are available in terms of the angular displacement of two shafts corresponding to the angular polar coordinates of said point, and the angular displacement of a third shaft corresponds to the distance polar coordinate of said point.

The apparatus, to be referred to in detail hereinafter, will be described by reference to the accompanying drawings, of which Figure 1 is a schematic circuit diagram of the invention which includes perspective views of the rotating discs; Figure 2 is an elevational view of the arrange-

ment of the discs and light responsive apparatus; Figure 3 is a graph showing the polar and rectangular coordinates of a point in space with respect to the reference plane xOy ; Figure 4 is an elevational view of one of the rotating discs in which fiducial marks are included; Figure 5 illustrates a modified form of disc; Figure 6 illustrates a computing system adapted to perform the additions performed by the devices 18 and 20 of Fig. 1 and to perform the multiplications performed by the devices 38, 40 and 50 of Fig. 1; Figure 7 is a wiring diagram of a set up system which is part of the computing system of Fig. 8; and Figure 8 is a wiring diagram of the two lower orders of the computing system of Fig. 6. Similar reference numerals are applied to similar elements throughout the drawings.

Referring to Fig. 1, a shaft 1, arranged to be rotated through an angle ϵ corresponding to the vertical angle, is securely fastened to the center of a relatively thin, transparent disc 2 having fiducial marks characteristic of the binary value of the sine of the angle of rotation. A mask 3, having a narrow slit 4, is rigidly supported so as to extend radially with respect to the disc 2, and is fixed in position. A plurality of light sources 5 are rigidly mounted in a fixed position adjacent one side of the disc 2, while an equal number of light sensitive devices 6 are rigidly mounted in back of the slit 4 in such a manner that the radial position of each of the light sensitive devices corresponds to the radial position of one of the light sources.

A second shaft 11 is disposed normal to the first shaft 1, in such a manner that their axes intersect. Second and third masks 13 and 23, which are arranged at right angles to each other, are rigidly connected to the second shaft 11 in such a manner that they mask a second disc 12, which is floated at its center upon the second shaft 11, and the periphery of which is in contact with the periphery of the first disc 2.

Fourth and fifth masking members 33 and 43, respectively, are also securely fastened to the second shaft 11 and arranged to mask a third disc 22, which also is floated at its center on the second shaft 11, and the periphery of which is in contact with the periphery of the first disc 2 at a point removed 180 degrees from the point of contact of the first and second discs 2 and 12, respectively. A fourth disc 32 is fastened to a third shaft 14 and includes a fixed radial mask 53. Light sources and light sensitive devices (not all shown) are rigidly arranged on the shaft 11 or to other fixed supports so that the light from the sources passes through the narrow slits in each of the masks in such a manner that the fiducial marks on the various discs vary the light falling on the light sensitive devices which generate potentials characteristic of the binary number corresponding to the particular function.

Each of the individual light sensitive devices disposed adjacent the masking element 13 is connected to a first electronic adding circuit 18 of the type described hereinafter. Similarly, the individual light sensitive devices disposed adjacent the fourth masking element 33 are also connected to the input of the first electronic counter circuit 19, whereby voltages corresponding to the binary numbers which are representative of the sines of the sum and difference of the horizontal and vertical angles are applied to this adding circuit. In a like manner the individual light sensitive devices disposed adjacent the slits in the third and

fifth masking elements 23 and 43 are connected to the input of a second electronic adding circuit 20, whereby voltages characteristic of the binary numbers corresponding to the cosines of the sum and difference of the angles are applied to this adding circuit.

The individual light sensitive devices 6, disposed adjacent the slit in the first masking element 3, are connected to the input of a first electronic multiplier circuit 30 of the type described hereinafter. The individual light sensitive devices 16, disposed adjacent the slit in the sixth masking element 53, are also connected to the input of the first multiplier unit 30, whereby the product of the binary quantities representative of the sine of the vertical angle and the distance are multiplied to derive a product proportional to the value of the rectangular coordinate z . Similarly, the output of the first electronic adding circuit 10 and the output of the individual light sensitive devices 16 are connected to the input of a second electronic multiplier circuit 40, whereby the product derived is proportional to the value on a second rectangular coordinate y . In like manner, the output of the second electronic adding circuit 20 and the individual light sensitive devices 16 are applied to the input of a third electronic multiplier circuit 50, from which a product is derived which is proportional to the value of the x rectangular coordinate. It should be understood that the digits of all values represented by voltages throughout the circuit are in terms of binary numbers characterized by the individual conditions of electronic circuits, such as trigger circuits of the Eccles-Jordon type described in the above-mentioned copending applications. It should also be understood that the values on the x , y and z coordinates derived from the multiplier circuits 50, 40 and 30, respectively, are also in terms of the electrical condition of trigger circuits of this type and are expressed in terms of binary numbers.

Fig. 2 is an elevational view which shows more clearly the constructional details of the rotating discs, masking elements and light responsive devices, already described. It should be understood that the particular constructional features disclosed herein are purely for the purpose of illustration, and that various mechanical modifications may be employed without departing from the spirit and scope of the invention.

Fig. 3 is a graph illustrating the rectangular coordinates x , y and z , respectively, of a point P in space, located a distance D from a reference point O on a reference line Ox , wherein the line OP forms a vertical angle A with its horizontal projection, and this projection forms an angle A with respect to a reference line Ox . The description included heretofore refers to the point P as determined by the coordinates illustrated in the graph.

Fig. 4 is an elevational view of a typical disc containing fiducial markings 7 representative of the binary value of a function of the angle of rotation of the disc. It should be understood that the particular characteristics and arrangement of the markings will be different from that illustrated and that the disc may be transparent with opaque fiducial markings, or vice versa or the disc may be arranged in any other manner to provide suitable actuation of the light sensitive devices described. For example, the disc may be in the form of a reflector having non-reflecting fiducial marks and arranged to reflect light from suitably disposed light sources, through an aper-

ture in a suitable mask, to a group of light sensitive devices. Various embodiments of light interrupters of this type are disclosed in the prior art. Similarly, the fiducial markings may be placed upon a carrier such as a photographic film wherein the distance of travel of the film corresponds to the angular displacement of a shaft or to the distance of the point P from the reference point, as desired.

On the disc of Fig. 4, the negative values of the sine are given in terms of complementary numbers. On the disc of Fig. 5, they are given in their actual values, it being remembered that these values are negative for the two lower quadrants. The disc of Fig. 4 has the advantage that it is readily usable with the adding systems 10 and 20 of Fig. 1 for the reason that a number A may be subtracted from a number B by adding the complementary A' to B and ignoring digital positions higher than the highest digital position of the number B . Thus if $B=1011$ and

$$A=0110, A \text{ inverted}=1001+1=1010 \text{ and}$$

$1011+1010=1.0101$. Ignoring the 1 in the highest place, there remains .0101 which is the difference between 0.1011 and 0.0110. The complementary of a binary number other than 0 is obtained by interchanging all digit zero's into one's and vice versa and adding one in the lowest place. The additional place, on the high power side (left), indicated in parentheses, is necessary if complementary numbers are used in additions or multiplications. The table of the negative values of the disc of Fig. 4 is as follows:

Angle X	Decimal Sin X	Binary	Complementary
0	0	(0)0.0000	(0)0.0000
7 $\frac{1}{2}$		(0)0.0010	(1)1.1100
15	.259	(0)0.0100	(1)1.1100
22 $\frac{1}{2}$		(0)0.0100	(1)1.1010
30	.500	(0)0.1000	(1)1.1000
37 $\frac{1}{2}$		(0)0.1010	(1)1.0110
45	.707	(0)0.1011	(1)1.0101
52 $\frac{1}{2}$		(0)0.1100	(1)1.0011
60	.866	(0)0.1101	(1)1.0010
67 $\frac{1}{2}$		(0)0.1110	(1)1.0001
75	.966	(0)0.1111	(1)1.0001
82 $\frac{1}{2}$		(0)0.1111	(1)1.0001
90	1.000	(0)1.0000	(1)1.0000

When an opaque sector of the disc is presented to a light source, the resulting potential is representative of the binary digit zero and, when the presented sector is transparent, the resulting potential is representative of the binary digit one. The location of the digit with respect to the binary point is determined by the radial position of the sector. The pulses by which these resulting potentials are established are applied through the switches 51 to 55 to the set-up units of the various elements of the computing system of Fig. 6. This computing system is disclosed and claimed in a copending application of Leslie E. Flory, Ser. No. 507,131, filed October 21, 1943.

This computing system is operable either to add numbers, potentials representative of the various digits of which are applied to the set-up system including units I to VII, or to multiply two numbers, potentials representative of which are applied respectively to the units I to VII of one set-up system and to the units 10 to 13 of the other set-up system. As utilized to perform the functions of the devices 10 and 20 of Fig. 1, it is an adder or accumulator. As utilized to perform the functions of the devices 30, 40 and 50 of Fig. 1, it is a multiplier.

The computing system includes a number of

similar channels. Thus, the first or lowest order channel includes an input capacitor 116, a set-up unit I, a shift capacitor 120, transfer amplifier 130, a differentiating circuit 140, and a totalizer unit comprising a set-up unit XI, a carry-over amplifier 150 and a carry-over transformer 60. The connections of the first and second of these channels are shown in Fig. 8 in connection with which the operation of the system is hereinafter explained in detail. It should be understood at this point, however, that the amplifiers 130, 131, etc., and 150, 151, etc., are biased to cut off when their corresponding set-up units are in a binary one condition and are biased below cutoff when their corresponding set up units are in a binary zero condition.

In the operation of the system to add numbers, pulses are applied through the capacitors 116, 116', etc., for establishing at the set-up unit output leads 124, 125, etc., potentials representative of the first number which is then transferred to the set-up units XI, XII, etc., by touching the switch 128 to its lowermost contact. The first number is then removed from the set-up devices I, II, etc., by touching the reset switch 51 (Fig. 7) to its contact and pulses dependent on the digits of the second number are applied to the input capacitors 116, 116', etc., thereby establishing at the least 124, 125, etc., potentials representative of the digits of the second number. This second number is then transferred to the set-up units XI, XII, etc., by again touching the switch to its lowermost contact. When this operation has been repeated for each of the numbers to be added, potentials representative of the digits of their sum are available at the totalizer output leads L and are applied to the multiplier units 38, 40 and 50 of Fig. 1.

Each of these multiplier units is similar to the system of Fig. 6. In the operation of this system as a multiplier, pulses dependent on the digits of the multiplicand are applied to the input capacitors 116, 116', etc., for establishing at the set-up unit output leads 124, 125, etc., potentials representative of the digits of the multiplicand. Pulses dependent on the digits of the multiplier are likewise applied to the input terminals of the set-up devices 70, 71, etc., for establishing at the contacts of the switch 128 to which the devices 70 to 73 are connected potentials representative of the digits of the multiplier.

With these potentials established as explained, the switch 128 is touched to the second contact from the bottom, thereby transferring the multiplicand to the set-up units XI, XII, etc., if the set-up unit 70 is in a binary one condition. If the unit 70 is in a binary zero condition, however, nothing is transferred to the units XI, XII, etc. The connections of the devices 70 to 73 are similar to those of the devices I, II, etc., with the exception that the stepping network may be omitted. Touching of the contact connected to the device 70, for example, transfers the multiplicand to the totalizer only when the unit 70 is in a binary one condition because only then are the grid potentials of the amplifiers 130 to 138 raised sufficiently to pass an impulse. The same thing is true of the units 71, 72 and 73. When the switch 128 engages its lowermost contact, the amplifiers 130 to 138 are likewise biased to a voltage at which pulses are passed to the units XI, XII, etc., from the units I, II, etc., which are in a binary one condition. In either case, the next step is the touching of the switch 128 to its clo-

sure contact for the purpose of shifting the multiplicand by one digital position. The switch 128 is then touched to its third contact from the bottom, thereby transferring or not transferring the 5 shifted multiplicand to the units XII, XIII, etc., depending on whether the unit 71 is in a binary one or a binary zero condition. Thereafter, the switch 128 is touched to its closure contact for again shifting the multiplicand by one digital position.

How the circuit of Fig. 6 functions in the apparatus of Fig. 1 will be understood if it is assumed (1) that the disks 2, 12 and 22 are of the type shown by Fig. 5, (2) that successive terminals of this figure are connected to the successive capacitors 116, 116', etc., of Fig. 8, and (3) that potentials derived from the disk 22 and representative of the distance D are established in the set-up devices 70 to 73.

Under these conditions, the procedure of deriving the rectangular component z involves (1) moving the switch 128 to its first contact thereby transferring the value $\sin \epsilon$ to the units XI, XII, etc., (2) closing and opening the switch 128 thereby shifting the value of $\sin \epsilon$ by one digital position, (3) moving the switch 128 to its second contact thereby transferring the shifted value of $\sin \epsilon$ to the units XI, XII, etc., and (4) continuing this process for the remaining digital positions of the value of D. As a result of this procedure, there is established at the indicators of the units XI, XII, etc., a set of potentials representative of twice the value of the rectangular coordinate z which may be determined by reading the indicators with the binal point moved one digital position to the left.

By closure of the switches 53 (one for each output lead of the disk 22 of Fig. 1), the value of $\sin (A-\epsilon)$ is likewise established in the units 40 I, II, etc., of the devices 10 and 40 of Fig. 1 and multiplied by the value of D so that potentials representative of the product $D \sin (A-\epsilon)$ are established in the units XI, XII, etc. The units I, II, etc., are then reset to zero and the switches 54 are closed to establish in the units I, II, etc., of the devices 10 and 40 of Fig. 1 potentials representative of the value of $\sin (A+\epsilon)$ which is multiplied by the value of D as previously explained to produce in the units XI, XII, etc., potentials representative of the product

$$D \sin (A+\epsilon)$$

The units XI, XII, etc., now have established in them potentials representative of the sum $[D \sin (A-E)] + [D \sin (A+\epsilon)] = D[\sin (A-E) + \sin A + \epsilon] =$ twice the value of the rectangular coordinate y which is derived by moving the binal point one digital position to the left.

In the same way, the sum of

$$D[\cos (A-\epsilon) + \cos (A+\epsilon)]$$

is established in the units XI, XII, etc. This sum is equal to twice the rectangular coordinate x and must be read with the binal point moved one digital position to the left in order to produce the true value of x.

As indicated by Fig. 1, the switches 53 (one for each digital position of the value of $\sin (A-\epsilon)$) and the switches 51 (one for each digital position of the value of $\cos (A-\epsilon)$) may be simultaneously operated as indicated by a broken line so that the values $D \sin (A-\epsilon)$ and $D \cos (A-\epsilon)$ are simultaneously established in the units 10-40 and 20-50. In the same way, the switches 52 and 54 may be simultaneously

operated to establish the value of $D \sin (A + \epsilon)$ in the units 10-40 and the value of $D \cos (A + \epsilon)$ in the units 20-50.

When these operations have been repeated for each digit of the multiplier, potentials representative of the product are available at the output leads L so that the three groups of potentials represent respectively the digits of numbers which are double the correct values of the x, y and z coordinates of the point P (Fig. 3). The real values are derived with sufficient accuracy by moving the binal point one digital position to the left.

The connections of the set-up units (Fig. 7) and their operation are for the most part familiar to those skilled in the art and are readily understood without detailed explanation.

Thus, each unit includes a pair of electron discharge devices 101-102, 111-112, 121-122, etc. Each pair of devices is so interconnected that only one of the devices is conducting at a given time. Current may be transferred from one device of a pair to the other by applying a negative pulse between the terminals 115. When the device 101 (in the case of unit I) is conducting, the unit I is in a binary one condition as indicated by the lighting of the lamp 113. When the device 102 is conducting, the unit I is in a binary zero condition. The same is true for all the other units which are arranged to provide at their output terminals 124-125, etc., potentials representative of successive digits of the number to be added or multiplied.

One feature not so well known to those skilled in the art is the reset system by which a negative pulse is applied through a switch s_1 and resistors 117, 118, 119, etc., to the grids of the devices 101, 111, 121, etc., for establishing all the units in a binary zero condition.

Another feature not so well known is the multiplicand shift system by which a negative pulse is applied through the capacitors 120, 120', 120'', etc., to the control grids of the tubes 101, 111 and 121 for shifting multiplicand one digital position as previously indicated. In explaining the operation of this shift system, it is assumed that the tubes 101, 111 and 122 are conducting. This condition of the circuit represents the binary number 011. In the system of Fig. 7, the unit 101-102 is intended to represent the lowest order of the binary number, the unit 111-112 the next to the lowest order of the number, etc.

The application of a negative pulse through the capacitors 120, 120' and 120'' operates to make the tube 102 conducting and the tube 101 non-conducting. It does not affect the condition of the tube 121 for the reason that this tube is already non-conducting. It starts to make the tube 111 non-conducting thereby producing a positive pulse which operates through the capacitor 123' to make the tube 121 conducting and the tube 122 non-conducting. The tube 111, however, is prevented from assuming a non-conducting state due to a positive pulse applied to its grid from the anode of the tube 101 through the capacitor 123 which may have a capacity of 100 μf . as compared to a capacity of the order of 3 μf . for the capacitors 120, 120', 120'', etc.

The circuit is now in a condition representing the binary number 110, the number having been shifted one digital position to the left.

If it be assumed that the tubes 101, 112 and 122 are conducting, the binary number set up in the circuit is 001. Under these conditions, the application of a negative pulse through the ca-

pacitors 120, 120' and 120'' causes current to be transferred from the tube 101 to the tube 102 but has no effect on the tubes 111 and 121. When current is transferred from the tube 101 to the tube 102, however, a positive pulse originating at the anode of the tube 101 is applied through the relatively large capacitor 123 to the grid of the tube 112 thereby transferring current from the tube 112 to the tube 111. Under these conditions, the binary number now set up in the circuit is 010, the number having been shifted one digital position to the left.

Fig. 8 as previously indicated, is a wiring diagram of the two lower order channels of Fig. 6, corresponding parts being identified by the same reference numerals in the two figures.

In the operation of these channels, a number is set up in the units I, II, etc., by applying to the contacts 115 pulses dependent on the various digits of the number, positive pulses are applied through the switch 128 for transferring the number to the totalizer set-up devices XI, XII, etc., and negative impulses are applied through the switch 129 for shifting the number by one digital position only when numbers are to be multiplied.

Thus assuming the binary number 01 to be set up in the units I and II and the set-up devices XI, XII, etc., to be in a binary zero position, amplifier 131, 150 and 151 are biased below cutoff and the amplifier 130 is biased to cutoff. Under these conditions, the application of a positive pulse through the switch 128 operates through amplifier 130, diode 160 and capacitor 170 to apply a negative pulse to the unit XI whereby this unit is converted to a binary one condition and the amplifier 150 is biased to cutoff. This follows as a result of the more negative voltage applied to the cathode of the diode 160 and to the grid of the amplifier 150 when current is drawn through the anode resistor of the amplifier 130.

A second positive pulse applied through the switch 128 operates through the amplifier 130 and the differentiating circuit 140 to produce positive and negative pulses 147 and 148 (see Fig. 6). The pulse 147 operates through the amplifier 150, the capacitor 172, the diode 161 and the capacitor 171 to change the unit XII to a binary one condition and to bias the amplifier 151 to cutoff. The pulse 148 operates through the diode 160 and the capacitor 170 to change the unit XI to a binary zero condition, thereby biasing the amplifier 150 beyond cutoff.

A third positive pulse applied through the switch 128 operates, as in the case of the first pulse, to change unit XI to a binary one condition and to bias the amplifier 150 to cutoff.

A fourth positive pulse applied through the switch 128 operates through the amplifier 130 and the differentiating circuit 140 to produce the positive and negative pulses 147 and 148. The positive pulse 147 operates through the transformer 60 and the amplifier 151 to apply a negative pulse to the unit XIII (Fig. 6) whereby it is converted to a binary one condition and the amplifier 152 is biased to cutoff and through the capacitor 172, the diode 161 and the capacitor 171 to apply a negative pulse to unit XII whereby it is converted to a binary zero condition and the amplifier 151 is biased beyond cutoff. The negative pulse 148 operates through the diode 160 and the capacitor 170 to apply a negative pulse to the unit XI whereby it is converted to a binary zero condition and the amplifier 150 is biased beyond cutoff.

A fifth positive pulse applied through the

switch 128 operates as in the cases of the first $\pi/3$ and third impulses to change unit XI to a binary one condition and to bias the amplifier 160 to cutoff.

Thus the application of five pulses has operated to set up in the units XI, XII, etc., a binary number 101 (5 in the decimal system) which is the sum of the numbers transferred from the set-up system I, II, etc., to the set-up system XI, XII of the totalizer.

Had the applied pulses been potentials representative of the digits of a multiplier, the switch 28 would have been touched to its closure contact after each transfer or non-transfer to shift the binary number 01 by one digital position so as to set up the resulting product in the units XI, XII, etc.

As is apparent from the foregoing discussion, an outstanding characteristic of the present invention is the provision of an improved apparatus and method of operation whereby trigonometric functions characteristic of the polar coordinates of a point are converted to the rectangular coordinates corresponding to such polar coordinates.

I claim as my invention:

1. A computer for translating the values of the polar coordinates of a point in space into voltages representative of the rectangular coordinates of said point which includes a first supporting means, a second supporting means, at least one fiducial scale representative of a predetermined function of an angular polar coordinate of said point on each of said supporting means, cooperative masking means respectively including a slit disposed in operable relation to said scales of both of said supporting means, means for displacing said first supporting means an amount representative of a first angular polar coordinate of said point, means for displacing said second supporting means an equal amount in the opposite sense, means for displacing said masking means an amount representative of a second angular polar coordinate of said point, first separate voltage generating means responsive to the exposed fiducial marks of each fiducial scale on said first supporting means, second separate voltage generating means responsive to the exposed fiducial marks of each fiducial scale on said second supporting means, means responsive to said generated voltages for deriving potentials representative of the digits of the value of a predetermined function of the sum and difference of said angles, means for deriving voltages representative of the digits of the value of the distance polar coordinate of said point, and means for deriving the product of said distance and said predetermined function of said combined angles.

2. In a device for converting the polar coordinates D, A and ϵ into rectangular coordinates x, y and z, the combination of means including three members bearing fiducial marks and rotatable together, means for deriving from said marks pulses in groups which are respectively representative of the values of D, the sines of ϵ , $(A+\epsilon)$ and $(A-\epsilon)$ and the cosines of $(A+\epsilon)$ and $(A-\epsilon)$; means for deriving the sum of said sine $(A+\epsilon)$ representative pulses and said sine $(A-\epsilon)$ representative pulses, means for deriving the sum of said cosine $(A+\epsilon)$ representative pulses and said cosine $(A-\epsilon)$ pulses, and means for multiplying each of said sum representative pulse groups and said sine ϵ pulse representative group by said D representative pulse group to derive

other groups of pulses which are representative of the values of $2x$, $2y$ and $2z$ respectively.

3. In a device for converting the polar coordinates D, A and ϵ into rectangular coordinates x, y and z, the combination of means including three members bearing fiducial marks and rotatable together, means for deriving from said marks pulses in groups which are respectively representative of the values of D, the sines of ϵ , $(A+\epsilon)$ and $(A-\epsilon)$ and the cosines of $(A+\epsilon)$ and $(A-\epsilon)$; electronic means for deriving groups of pulses respectively representative of the sum of said sine $(A+\epsilon)$ and sine $(A-\epsilon)$ representative pulses and the sum of said cosine $(A+\epsilon)$ and cosine $(A-\epsilon)$ representative pulses; and means for deriving groups of pulses which are the products of said D representative pulses multiplied by said sine ϵ representative pulses, said D representative pulses multiplied by said sine

20 $(A+\epsilon) + \sin(A-\epsilon)$

representative pulses and said D representative pulses multiplied by said cosine

25 $(A+\epsilon) + \cos(A-\epsilon)$

representative pulses.

4. In a device for converting the polar coordinates D, A and ϵ into rectangular coordinates x, y and z, the combination of a first member rotatable in accordance with the value of ϵ and bearing marks representative of sine of ϵ , means selectively responsive to said marks for producing electrical pulses representative of different values of the sine of ϵ , second and third members rotatable by said first member in opposite directions in accordance with the value of A and bearing marks representative of the sine and the cosine of A, means selectively responsive to the marks of said second member for producing electrical pulses representative of sine $(A+\epsilon)$ and $\cos(A+\epsilon)$, means selectively responsive to the marks of said third member for producing electrical pulses representative of sine $(A-\epsilon)$ and cosine $(A-\epsilon)$, means for deriving a first sum of pulses equal to said sine $(A-\epsilon)$ plus said sine $(A+\epsilon)$ representative pulses, means for deriving a second sum of pulses equal to said cosine $(A-\epsilon)$ plus said cosine $(A+\epsilon)$ pulses, a fourth member rotatable in accordance with the value of D and bearing marks representative of D, means selectively responsive to said D representative marks for producing pulses representative of different values of D, and means for deriving products respectively equal to the number of said D representative pulses times the number of said sine ϵ representative pulses, the number of said D representative pulses times the number of said first sum representative pulses and the number of said D representative pulses times the number of said second sum representative pulses.

60 JAN A. RAJCHMAN.
